GORDON E. BURNS, OF TOLEDO, OHIO, ASSIGNOR TO THE COLUMBIA BURNER CO., OF TOLEDO, OHIO, A CORPORATION OF OHIO

HIGH AND LOW FLAME CONTROL FOR GAS BURNERS

Application filed October 12, 1931. Serial No. 568,231.

This invention relates to a high and low flame control for gas burners with special reference to their use in heating plants.

The general object of the invention is to provide improved means for controlling the supply of gas to the burner in accordance with the amount of heat required to maintain a uniform temperature in the room or rooms to be heated. In connection with the invention, there is a comparatively large main supply orifice having a valve which is open when a high flame is required and a smaller by-pass orifice having a valve which is held open while the main valve is closed, if only a low flame is required to maintain the desired temperature, as is the case in moderate weather. If the room temperature is such that no heat is called for, of course the by-pass valve is also closed and only the pilot is kept burning.

My invention will be more particularly described in connection with the accompanying drawings, in which—

Figure 1 is a horizontal section through a control device constructed according to the invention, the section being taken approximately on the line 1—1 of Fig. 2;

Figure 2 is a vertical section taken substantially on the line 2—2 of Fig. 1;

Figure 3 is a section taken substantially on the line 3—3 of Fig. 2;

Figure 4 is a section taken substantially on the line 4—4 of Fig. 3, showing particularly the device for opening the low flame valve;

Figure 5 is an enlarged plan view of the motor and relays used in controlling the gas supply, the view taken substantially on the line 5—5 of Fig. 3;

Figure 6 is a wiring diagram showing the thermostatic control for the motor and relays; and

Figure 7 is a partly diagrammatic view showing a modified construction and wiring in which a solenoid is used in place of the motor.

The control device to which my invention relates comprises a casing 9 provided with an inlet 10 adapted to be connected to the gas main and an outlet 11 which leads to the burner. The inlet 10 leads into a chamber 12

which is provided with a comparatively large main orifice 13 leading into a chamber 14, whence the gas flows through the passageway 15 and chamber 16 to the outlet 11. A valve 17 controls the flow of gas through the main orifice 13 and may be termed the high flame valve since a full flow of gas for a high flame can be obtained only when this valve is open.

The passageway 15 is restricted to the desired extent to suit the maximum desired requirement of the particular installation by an adjustable plug or valve 18. The valve 18 is mounted in a screw threaded bore 19 and after it is set the outer end of the bore is closed by a plug 20 the head of which has a ground seat. The passageway 15 in the present instance opens into a chamber 16 from which the outlet 11 leads to the burner to be controlled. It is also desirable to provide a lateral opening 21 in the passageway 15 opposite the valve 18 in order to prevent swirling of the gas as it enters the chamber 16.

When the valve 17 is open it acts normally as a pressure regulator. In connection with the pressure regulator, an auxiliary casing 21 is mounted above the chamber 12 and is divided by a flexible diaphragm 22 into a lower compartment 23 and an upper compartment 24. Communication between the diaphragm chamber 23 and the gas inlet chamber 12 is closed by an auxiliary diaphragm 25 therebetween.

A tubular stem 26 is secured centrally to the diaphragms 22 and 25 and extends through the valve orifice 13 and through a guide opening 27 into the chamber 16. The stem 26 carries the valve 17 which is adapted to seat against the lower edge of the orifice 13 to close the communication between the chambers 12 and 14 and by a downward movement from its seat to effect an opening of such communication. This movement of the valve 17 when it is functioning as a pressure regulator is determined by the pressure in the chamber 14 which communicates through a small passageway 28 with the chamber 23 beneath the diaphragm 22.

Under certain conditions however, as for example, when a high flame at the burner is not required, the valve 17 is completely closed,

regardless of the pressure in the chamber 14, by an arm 29 secured to a rock shaft 30, said rock shaft being held in this position by a spring 31. Under the conditions hereinafter explained, the shaft 30 is rocked in the opposite direction through the medium of an arm 32, so that the arm 29 disengages the valve 17 and permits it to act as a pressure regulator. The rock shaft 30 also has a connection 33 for operating an air door or damper in accordance with the rate of gas flow through the orifice 13. The structure and operation of the air damper do not constitute a part of the present invention and need not be more particularly described.

The chamber 12 also has a port 34 leading into a chamber 35, whence gas is supplied to the usual pilot. This port 34 may be opened or closed by means of a screw threaded stem 36 having at its inner end a head 37 which has a ground seat on the port 34, when closed, and has a ground seat, when open, against the inner end of the bushing 38 in which the stem 36 is mounted.

When a moderate or low flame is required, the valve 17 is closed and a smaller flow of gas is supplied to the burner from the chamber 12 through an orifice 39 and chamber 40. The rate of flow to the burner for providing a low flame may be fixed as desired by means of an adjustable plug or valve 41 which is mounted in a threaded bore 42 opposite the orifice 39. After the plug 41 has been adjusted to restrict the flow through the orifice 39 as desired, the outer end of the bore 42 is closed by a plug 43 which has a head with a ground seat.

The low flame supply of gas is by-passed around the high flame valve 17, as indicated by the arrows in Fig. 1. It passes from the orifice 39 downwardly in the chamber 40, through the passageway 44 and valve chamber 45, when the valve 46 is open, and thence through the port 47 into the chamber 14. The valve 46, which may be termed the low flame valve, has a stem 48 on its outlet side and this stem is provided outside of the gas conduit with a head 49. The stem is provided with packing 50 and an expansile coil spring 51, between the head 49 and packing 50 tends to close the valve 46, and when the valve is opened by pressure against the outside of head 49, the spring compresses the packing to prevent leakage of the gas.

As illustrated in Figs. 1 to 6 inclusive, the operations of the valves 17 and 46 are controlled, in accordance with the amount of heat required, through the medium of a motor 52, high flame relay 53, low flame relay 54 and a thermostat 55 having two switches 56 and 57. When the motor 52 is energized, the main control shaft 58 is driven through the medium of speed reduction gearing 59 until it completes a partial revolution. The circuit through the motor 52 is then auto-

matically broken by means hereinafter described and the shaft 58, when released, is returned with its driving mechanism to initial position by a spring 60.

A disk 61 is secured to the shaft 58 and on one face carries a pin 62 which is connected by a link 63 to the arm 32 on the valve control shaft 30. When the motor is driven forwardly, the link 63 moves downwardly to rock the shaft 30, moving the arm 29 away from the valve 17 and permitting the latter to open and to function normally as a pressure regulator.

The disk 61 has a second pin 64 diametrically opposite to the pin 62 and on the opposite face of the disk. As the motor is driven forwardly, the pin 64 raises the long arm of a low flame valve lever 65 which is fulcrumed at 66 and which has a heel 67 engageable with the head 49 of the low flame valve 46 to open the latter. The free end of the long arm of the lever 65 has a latch rack 68 adapted to be engaged by a bolt 69 which is advanced against the resistance of a spring 69^a when the low flame relay 54 is energized, thus locking the low flame valve 46 in open position.

A latch rack 79 is also secured to the shaft 58 and is adapted to be engaged by the bolt 71 which is advanced by the high flame relay 53 in opposition to a spring 71^a to lock the shaft 58 in advanced position when the high flame relay 53 is energized.

Referring to the wiring diagram in Fig. 6, the numeral 72 indicates a pilot thermostat which is adapted to shut off the gas entirely from the pilot, as well as from the main burner, in case the pilot for any reason becomes extinguished. As far as the present invention is concerned, however, it may be assumed that the pilot is functioning normally.

When the temperature in the region of the thermostat 55 indicates that a moderate amount of heat is required, the switch 56 closes. There is then a closed circuit from the transformer 73, through line 74, switch 56, line 75, switch 76 and line 77 to the motor 52 and thence through line 78, switch 79 and line 80 to the transformer. As the motor is thus operated to rock the shaft 58, it rocks the shaft 30 through the medium of the link 63 to open the main valve 17 and insure quick and full ignition and at the same time raises the long arm of lever 65 and opens the low flame valve 46. At this time, a lug 81 on the lever 65 closes the switch 82. This closes a shunt from line 75 through line 83, switch 82, low flame relay 54 and line 84, energizing the low flame relay 54, which advances the bolt 69 to engage the latch rack 68 and lock the low flame valve open, at the same time moving the bolt 69 away from the pivoted arm 76^a, permitting switch 76 to open and break the circuit through motor 52. This

allows the motor to resume its initial position and causes the shaft 30 and arm 29 to close the main valve 17. Thus the main valve 17 remains open only long enough to insure full ignition. The low flame relay 54 remains energized and the low flame valve 46

5

remains open until the temperature rises sufficiently to open the switch 56 and break the circuit through the relay.

If the heat furnished by the low flame is not sufficient to maintain the desired temperature, the second thermostat switch 57 closes and, although the switch 76 is open, the circuit through the motor 52 is completed through line 74, switch 57, lines 85 and 77, 10 to the motor and thence through line 78, switch 79 and line 80. The shaft 58 is now advanced until a cam 86 secured thereto closes a switch 87, closing a shunt from line 77 through line 88, switch 87, line 89, high flame relay 53, and line 90 to line 80. The high flame relay, thus energized, advances the bolt 71 in opposition to spring 71^a into engagement with the latch rack 70 to lock the shaft 58, leaving the high flame valve 17 15 open, while at the same time pivoted arm 79^a is released to permit switch 79 to open and break the circuit through the motor. Both valves 17 and 46 now remain open until such time as the thermostat switch 57 is opened 20 to break the circuit through the high flame relay 53, thus permitting the return of shaft 30 to its initial position and closing the valve 17. The valve 46, however, remains open 25 until both switches 56 and 57 are open.

It is also preferred to make provision for manual control in case the electric current fails. For this purpose a knob 91 is secured to the outer end of the shaft 58 and carries 30 the cam 86. A pin 92 is carried by the knob 91 and is normally held in retracted position by a spring 93. In the manual control of the device, the shaft 58 is advanced until the switch 87 is closed and until the pin 92 35 is in position to be advanced and interlocked with the switch 94, closing the latter. When the shaft 58 is in this position, the high flame valve 17 is open and will remain so until it is again closed by manipulation of the knob 91 or until the electric current is restored. The moment the electric current is restored, 40 the motor circuit is completed through lines 80 and 90, high flame relay 53, line 89, switch 87, line 88 to the motor and thence through switch 94 and line 95 back to the transformer. The energizing of the motor 52 will immediately release the pin 92 from the switch 94, 45 permitting the latter to open and at once restoring the thermostat control.

60 In the modified form of the invention illustrated in Fig. 7, a solenoid 96 is substituted for the motor 52. The core 97 of this solenoid carries a cross head 98 which is connected by a link 63^a to the arm 32. A modified form of lever 65^a is substituted for the

lever 65 and is formed with a latch rack 68^a which has the same function as the latch rack 68. The long arm of the lever 65^a has a bifurcated end 99 which straddles the solenoid core 97 and rests against the cross head 98.

When the first thermostat switch 56 is closed, calling for a small amount of heat, a circuit is closed from the transformer 73 through line 74, switch 56, line 75, switch 100, line 101, solenoid 96 and lines 102 and 80. The solenoid 96, thus energized, raises the core 97 and through the link 63^a rocks the shaft 30 to open the main valve 17, at the same time, through the medium of the cross head 98, raising the long arm of the lever 65^a and opening the low flame valve 46. At the same time, a lug 103 on the lever 65^a closes the switch 104. This closes a shunt from line 75 through low flame relay 54, line 105, switch 104 and line 106. The low flame relay 54, thus energized, advances the bolt 69 to engage the latch rack 68^a and lock the low flame valve open, at the same time moving the bolt 69 away from the pivoted arm 76^a, 85 permitting the switch 100 to open and break the circuit through the solenoid 96. This allows the solenoid core 97 to resume its initial position and cause the shaft 30 and arm 29 to close the main valve 17. Thus the main 90 valve 17 remains open only long enough to insure full ignition. The low flame relay 54 remains energized and the low flame valve 46 remains open until the temperature rises sufficiently to open the switch 56 and break the 95 circuit through the relay.

If the heat furnished by the low flame is not sufficient to maintain the desired temperature, the second thermostat switch 57 closes and, although the switch 100 is open, the circuit through the solenoid 96 is completed through line 74, switch 57, line 85, switch 107 and line 108 to the solenoid and thence through lines 102 and 80. The core 97 is now raised until the cam 109 secured thereto rocks a bell crank 110, which is fulcrumed at 111, to open the switch 107 and close the switch 112, thus closing a shunt from line 85 through switch 112, line 113, high flame relay 53, line 102 and line 80. The high flame relay, thus energized, advances the bolt 71 in opposition to spring 71^a into engagement underneath a shoulder 70^a on the core 97 to lock the shaft 30, leaving the high flame valve 17 open while at the same 110 time the switch 107 is opened to break the circuit through the solenoid. Both valves 17 and 46 now remain open until such time as the thermostat switch 57 is opened to break the circuit through the high flame relay 53, 115 thus retracting the bolt 71 and permitting the return of shaft 30 to its initial position and closing the valve 17, the arms of the yoke 99 being far enough apart to allow the shoulder 70^a to pass between them. The valve 46 re- 120 125 130

mains open until both switches 56 and 57 are open.

From the foregoing description, it will be understood that, with my control device, the temperature in the space to be heated may be controlled within very narrow limits. In moderate weather, instead of running the burner with the high flame alternately off and on, a uniform temperature will be maintained by means of the low flame control. It should also be noted that, as the temperature of the room cools off enough to close the first switch, the main high flame valve is at first opened momentarily, as well as the low flame valve, so that a high flame is provided to insure quick and full ignition. The main valve then immediately closes and the burner drops back to a low flame and remains there until the low flame proves insufficient to maintain the desired temperature. Then the second thermostat switch closes and the main valve is opened to turn on the high flame, which is maintained until said second thermostat switch opens. If the room becomes warm enough to open both thermostat switches, the flow of gas to the burner is entirely cut off until the first thermostat switch is again closed. Although normally, as the first thermostat switch closes, the low flame will maintain the desired temperature for a considerable period of time, it will be understood that in first starting up the furnace upon the approach of winter or in starting up in the morning, if both thermostat switches are closed substantially at the same time, the high flame will be at once turned on and will remain on until the desired temperature is reached.

It will also be noted that the circuit through the motor or the solenoid is maintained only long enough to open the valves, thus consuming very little electric current. The valves are then locked by the operation of the relays, which draw comparatively little current.

While I have explained the invention in considerable detail, it is to be understood that the same may be considerably modified in other ways without departing from the scope of the appended claims.

What is claimed is:

1. In a control device for a gas burner, means for automatically establishing and maintaining a predetermined flow of gas during the existence of a predetermined range of temperature in the space to be heated, and means for establishing and maintaining a relatively larger flow of gas during the existence of a lower temperature, said last mentioned means being also effective to turn on temporarily the larger flow of gas as the temperature drops into said predetermined range.

2. In a control device for a gas burner, means for supplying gas for a pilot, means

in addition to the pilot supply for supplying either a large flow or a relatively small flow of gas, and means, operable when a small amount of heat is required, first to turn on said large flow to insure full ignition and then automatically to drop back immediately to said relatively small flow.

3. In a control device for a gas burner, the combination with a thermostat, of means actuated by the thermostat at one temperature to supply a relatively small flow of gas, and means actuated by the thermostat at a predetermined lower temperature to supply a larger flow of gas, said last mentioned means being also effective to turn on temporarily the larger flow of gas as the cooling thermostat reaches the first mentioned temperature.

4. In a control device for a gas burner, the combination with a thermostat, of means actuated by the thermostat at one temperature to initially turn on a large flow of gas to insure quick and full ignition and immediately thereafter to establish and maintain a relatively small flow, and means for maintaining a supply of gas for a pilot independently of said relatively small flow.

5. In a control device for a gas burner, the combination with a thermostat, of means actuated by the thermostat at one temperature to initially turn on a large flow of gas to insure quick and full ignition and immediately thereafter to establish and maintain a relatively small flow, and means to reestablish and maintain continuously said large flow of gas when the temperature at the thermostat falls below a predetermined point.

6. In a control device for a gas burner, the combination with a thermostat provided with two switches adapted to be closed successively as the temperature drops, of electrical means actuated by the closing of the first switch to establish and maintain a predetermined flow of gas, and means actuated by the closing of the second switch to establish and maintain a larger flow of gas.

7. In a control device for a gas burner, the combination with a thermostat provided with two switches adapted to be closed successively as the temperature drops, of electrical means actuated by the closing of the first switch, first to turn on temporarily a large flow of gas to insure quick and full ignition and immediately thereafter to establish and maintain a smaller flow of gas, and means actuated by the closing of the second switch to reestablish and maintain the larger flow of gas.

8. In a control device for a gas burner, the combination with a thermostat provided with two switches adapted to be closed successively as the temperature drops, of electrical operating means temporarily energized by the closing of either one or both of the thermostat switches to turn on gas for a high

- flame, a low flame relay having a circuit which is maintained when the first thermostat switch is closed, and locking means held by the low flame relay when energized, to maintain the low flame gas supply.
- 5 9. In a control device for a gas burner, the combination with a thermostat provided with two switches adapted to be closed successively as the temperature drops, of electrical operating means temporarily energized by the closing of either one or both of the thermostat switches to turn on gas for a high flame, relays controlled by the respective thermostat switches, and means actuated by the respective relays, when energized, to maintain respectively the low flame gas supply or the high flame gas supply after said electrical operating means is de-energized.
- 10 10. In a control device for a gas burner, the combination with a thermostat provided with two switches adapted to be closed successively as the temperature drops, of electrical operating means temporarily energized by the closing of either one or both of the thermostat switches to turn on gas for a high flame, means operable as long as both thermostat switches are closed, to maintain a high flame gas supply after said electrical operating means is de-energized, and means operable as soon as one thermostat switch is closed to maintain a low flame gas supply.
- 15 11. In a control device for a gas burner, a supply line having a main orifice, a high flame valve therefor, a by-pass having a smaller orifice, a low flame valve for said smaller orifice, means for automatically maintaining the low flame valve open during a predetermined range of temperature in the space to be heated, and means for automatically maintaining the high flame valve open during the existence of a lower temperature, said last mentioned means being also effective to open the high flame valve temporarily as the temperature drops into said predetermined range.
- 20 12. In a control device for a gas burner, a supply line having a main orifice, a high flame valve therefor, a by-pass having a smaller orifice, a low flame valve for said smaller orifice, and means, operable when a small amount of heat is required, first to open the high flame valve temporarily to insure quick and full ignition and then to maintain the low flame valve open as long as any heat is required.
- 25 13. In a control device for a gas burner, a supply line having a main orifice, a high flame valve therefor, a by-pass having a smaller orifice, a low flame valve for said smaller orifice, a thermostat, means actuated by the thermostat at one temperature to establish and maintain the low flame valve in open position, and means actuated by the thermostat at a predetermined lower temperature to establish and maintain the high flame valve in open position, said last mentioned means being also effective to open the high flame valve temporarily as the cooling thermostat reaches the first mentioned temperature.
- 30 14. In a control device for a gas burner, a supply line having a main orifice, a high flame valve therefor, a by-pass having a smaller orifice, a low flame valve for said smaller orifice, a thermostat, means actuated by the thermostat at one temperature to open both valves to insure quick and full ignition and immediately thereafter to close the high flame valve while maintaining the low flame valve in open position until heat is no longer required.
- 35 15. In a control device for a gas burner, a supply line having a main orifice, a high flame valve therefor, a by-pass having a smaller orifice, a low flame valve for said smaller orifice, a thermostat, means actuated by the thermostat at one temperature to initially open both valves to insure quick and full ignition and immediately thereafter to close the high flame valve while maintaining the low flame valve open, and means to re-establish and maintain continuously the high flame valve in open position when the temperature falls below a predetermined point.
- 40 16. In a control device for a gas burner, a supply line having a main orifice, a high flame valve therefor, a by-pass having a smaller orifice, a low flame valve for said smaller orifice, a thermostat provided with two switches adapted to be closed successively as the temperature drops, electrical means actuated by the closing of the first switch to establish and maintain the low flame valve in open position, and means actuated by the closing of the second switch to establish and maintain the high flame valve in open position.
- 45 17. In a control device for a gas burner, a supply line having a main orifice, a high flame valve therefor, a by-pass having a smaller orifice, a low flame valve for said smaller orifice, a thermostat provided with two switches adapted to be closed successively as the temperature drops, electrical means actuated by the closing of the first switch to open both valves to insure quick and full ignition and immediately thereafter to close the high flame valve while maintaining the low flame valve open, and means actuated by the closing of the second switch to re-establish and maintain the high flame valve in open position.
- 50 18. In a control device for a gas burner, a supply line having a main orifice, a high flame valve therefor, a by-pass having a smaller orifice, a low flame valve for said smaller orifice, a thermostat provided with two switches adapted to be closed successively as the temperature drops, electrical operating means temporarily energized by the closing of one or both of the thermostat

- switches to turn on both valves, a low flame relay having a circuit which is maintained when the first thermostat switch is closed, and locking means held by the low flame relay, when energized, to maintain the low flame valve open. 5
19. In a control device for a gas burner, a supply line having a main orifice, a high flame valve therefor, a by-pass having a smaller orifice, a low flame valve for said smaller orifice, a thermostat provided with two switches adapted to be closed successively as the temperature drops, electrical operating means temporarily energized by the closing of one or both of the thermostat switches to turn on both valves, relays controlled by the respective thermostat switches, and means actuated by the respective relays, when energized, to maintain the respective valve open after said electrical operating means is de-energized. 10
20. In a control device for a gas burner, a supply line having a main orifice, a high flame valve therefor, a by-pass having a smaller orifice, a low flame valve for said smaller orifice, a thermostat provided with two switches adapted to be closed successively as the temperature drops, electrical operating means temporarily energized by the closing of one or both of the thermostat switches to turn on both valves, means automatically operable, as soon as both thermostat switches are closed to hold the high flame valve open after said electrical operating means is de-energized, and means automatically operable as soon as one thermostat switch is closed, to hold the low flame valve open. 15
21. In a control device for a gas burner, a thermostat provided with two switches adapted to be closed successively as the temperature drops, electrical operating means energized when both of said switches are closed, to turn on gas for a high flame, means for maintaining said high flame until one of said switches opens and for subsequently maintaining a lower flame until both switches are open or both switches closed. 20
22. In a control device for gas burners, means for automatically establishing and maintaining either a large flow of gas to the burner or a relatively small flow, depending upon the amount of heat required to maintain the desired temperature, means associated with the first mentioned means to temporarily turn on the larger flow of gas when heat is first demanded, and means for adjustably predetermining the rate of said small flow. 25
23. In a control device for gas burners, means for automatically establishing and maintaining a relatively small flow of gas during the existence of a predetermined range of temperature in the space to be heated, means for establishing and maintaining a relatively large flow of gas during the ex- 30
- istence of a lower temperature, said last mentioned means being also effective to turn on temporarily the larger flow of gas as the temperature drops into said predetermined range, and means for adjustably predetermining the rate of said small flow. 70
24. In a control device for gas burners, a supply line having a main orifice, a high flame valve therefor, a by-pass having a small orifice, a low flame valve for said smaller orifice, means for automatically establishing and maintaining either valve in open position, depending upon the amount of heat required in the space to be heated, means associated with the first mentioned means to temporarily open the high flame valve when heat is first demanded, and means for adjustably restricting the flow of gas to said smaller orifice. 75
